ROCKER ARM CONSTRUCTION

Clayton Farris, Newark, N. J., assignor to The
Trucktor Corporation, Newark, N. J., a corpora-
tion of Delaware

Application May 26, 1937, Serial No. 144,810

5 Claims. (Cl. 280—104)

The present invention relates to rocker arm constructions and embodies more particularly an improved form of rocker arm construction wherein the structure is formed to facilitate proper lubrication thereof during operation. A further characteristic of the present invention resides in the fact that the construction is such as to facilitate the accurate assembly of the elements of the rocker arm in order that it may be adapted for use in connection with varying assemblies.

The invention is of particular utility in connection with spring suspensions wherein dual axles are used to support a vehicle frame. In such constructions, it is frequently desired to equalize the action of the springs which are carried by the two axles and this may be done by means of shackle connections between adjacent ends of the springs upon each side of the vehicle and a rocker arm which is journaled upon the vehicle. Proper lubrication of this rocker arm during operation becomes an extremely important matter and an object of the present invention is to provide a rocker arm construction wherein lubrication thereof is carried out effectively during operation.

A further object of the invention is to provide a rocker arm construction wherein one or more of the journaled members may be secured in a desired position with respect to the rocker arm in order that the rocker arm assembly may be adapted for varying types of construction.

Further objects of the invention will be apparent as it is described in greater detail in connection with the accompanying drawing, wherein:

Figure 1 is a view in side elevation showing a spring suspension wherein a rocker arm is embodied, the rocker arm being constructed in accordance with the present invention.

Figure 2 is an enlarged view in side elevation, showing the rocker arm of Figure 1.

Figure 3 is a plan view partly broken away and in section, showing the rocker arm construction.

Referring to the above drawing, Figure 1 illustrates a vehicle side frame member 10 to which a bracket 11 is secured. Dual axles 12 and 13 are mounted upon the frame by means of springs 14 and 15, respectively, the adjacent ends of these springs being connected to shackle members 16 and 17, respectively. The spring 14 may be connected to shackle members 16 through a link 18 and the lower ends of the links 16 and 17 are connected to a rocker arm 19, by means of suitable journal connections to be described hereinafter. The foregoing elements, save the rocker arm, form no part of the present invention but simply serve to illustrate the manner in which the

rocker arm of the present invention may be used. With reference to Figures 2 and 3, the arm 19 is illustrated as being formed with a hollow interior shown in dotted lines at 20 in Figures 2 and 3. The arm is provided with a journal bearing 21 by means of which it may be journaled upon a supporting member such as the bracket 11. The ends of the arms are formed with bearings 22 and 23 in order that such ends may be journaled to suitable connecting members such as the links 16 and 17 in Figure 1.

In assembling the rocker arm for use as illustrated in Figure 1, it is sometimes necessary to have the bearing 22 positioned in one axial position, whereas, in other constructions, this axial position must be changed. For example, in one vehicle, the lateral position of spring 14 with respect to the frame 10 and bracket 11 may vary with respect to the position of these elements in another construction. In order to provide for such variations, the present invention provides a structure and method by means of which the rocker arm may be readily adapted for such varying installations. Accordingly, as illustrated in Figure 3, the bearing 22 consists of a sleeve 24 which is received within an aperture 25 formed in the arm 19. When positioned in a proper axial position, the sleeve 24 is welded to the arm, as illustrated at 26. In this fashion, a standard rocker arm construction may be adapted effectively for use in connection with varying structures.

In order that the bearings 21, 22 and 23 may be effectively lubricated, they are provided with bores 27 which are preferably formed adjacent the upper portions thereof. These bores form oil ducts which communicate with the interior of the arm. Plugs 28 may be provided in the rocker arm where it is necessary to drill through the structure thereof in order that the boring or duct work 27 may be formed. An aperture provided with a filler plug 29 is provided in the upper portion of the arm in order that a lubricant may be introduced thereto. In operation, as the arm pivots about the journal bearing 21, the lubricant is splashed about and falls in the bores 27 in order that the journals may be effectively lubricated. It is to be noted that normally the level of the lubricant within the rocker arm need not reach the bores 27 inasmuch as effective lubrication is accomplished during operation by reason of the splashing as above described.

While the invention has been described with reference to the specific construction shown in

the accompanying drawing, it is not to be limited
save as defined in the appended claims.

I claim:

1. A rocker arm comprising a hollow body
adapted to hold a quantity of lubricant, bearing
means carried by said body adapted to receive a
horizontal supporting journal, whereby the same
will rock in a vertical plane, additional bearing
means carried by said body, the upper portion
only of at least one of said bearing means being
provided with a lubricating passage communicat-
ing with the interior of said body, said passage
being disposed at a higher elevation than the
quantity of lubricant when the arm is in a hori-
zontal position, and means for introducing lu-
bricant into said body.
2. A rocker arm for vehicle spring suspensions
comprising a hollow body adapted to hold a
quantity of lubricant, said body having means for
mounting same for rocking movement in a ver-
tical plane, bearing means adjacent the ends of
said body adapted to receive spring connections,
the upper portion only of said bearing means
being provided with a lubricating passage com-
municating with the interior of said body dis-
posed at a higher elevation than the quantity of
lubricant when the arm is in a horizontal position,
and means for introducing lubricant into said
body.
3. A rocker arm for vehicle spring suspensions
comprising a hollow body adapted to hold a
quantity of lubricant having bearing means inter-
mediate the ends thereof for supporting the body
on a vehicle so that the same may rock in a

vertical plane, bearing means adjacent the ends
of said body, all of said bearing means lying sub-
stantially in a common plane, the upper portion
only of each of said bearing means being provided
with a lubricating passage communicating with
the interior of said body, said passage being dis-
posed at a higher elevation than the quantity of
lubricant when the arm is in a horizontal posi-
tion, and means for introducing lubricant into
said body.

4. The method of manufacturing a rocker arm
for vehicle spring suspensions comprising the
steps of forming a hollow body having means by
which the body is adapted to be mounted for rock-
ing movement, forming an aperture through the
hollow body, inserting a bearing-forming sleeve
in a desired position in the aperture, welding the
sleeve to the walls of said body, and forming
a lubricating passage through the upper portion
of the sleeve.

5. The method of manufacturing a rocker arm
for vehicle spring suspensions comprising the
steps of forming a hollow body containing a bear-
ing structure by which the body is adapted to be
mounted for rocking movement, forming an aper-
ture through the hollow body, inserting a bear-
ing-forming sleeve in a desired position in the
aperture, welding the sleeve to the walls of said
body, and forming a lubricating passage through
the upper portion of said bearing structure and
said bearing-forming sleeve for communication
with the interior of said hollow body.

CLAYTON FARRIS.
